(57) **CLAIM**

The ornamental design for a leaflet for a prosthetic heart valve, as shown and described.

DESCRIPTION

FIG. 1 is a perspective view of the leaflet, as viewed from the front, top, and one side thereof.

FIG. 2 is a front elevation view of the leaflet of FIG. 1, the back elevation view being identical to the front elevation view.

FIG. 3 is a left side elevation view of the leaflet of FIG. 1, the right side elevation view being identical to the left side elevation view.

FIG. 4 is a top plan view of the leaflet of FIG. 1; and,

FIG. 5 is a bottom plan view of the leaflet of FIG. 1.
